United States Patent

Des. 241,857
Patented Oct. 12, 1976

241,857

COMBINED TELEPHONE PUSHBUTTON SHIELD AND RETAINING PLATE THEREFOR

Lavern Dale Wulf, Harrisburg, Pa., assignor to
AMP Incorporated, Harrisburg, Pa.

Filed Nov. 11, 1975, Ser. No. 630,858

Term of patent 14 years

Int. Cl. D14—03

U.S. Cl. D26—14 A

Fig. 3

FIG. 4FIG. 5FIG. 6

FIG. 1 is a perspective view of a combined telephone pushbutton shield and retaining plate therefor showing my new design;

FIG. 2 is a top plan view thereof;

FIG. 3 is a side elevational view thereof;

FIG. 4 is a bottom plan view thereof;

FIG. 5 is a rear elevational view thereof; and

FIG. 6 is a front elevational view thereof.

We claim:

The ornamental design for a combined telephone pushbutton shield and retaining plate therefor, as shown.
